Primary Examiner—Robert A. Delehanty*(74) Attorney, Agent, or Firm*—Armstrong Teasdale LLP(57) **CLAIM**

I claim the ornamental design for a curvaceous carton, as shown and described.

DESCRIPTION

FIG. 1 is a front perspective view of the curvaceous carton of our new design.

FIG. 2 is a right side elevational view of the carton shown in FIG. 1.

FIG. 3 is a left side elevational view of the carton shown in FIG. 1; and,

FIG. 4 is a rear elevational view of the carton shown in FIG. 1.

The top and the bottom are flat and devoid of surface ornamentation.
